UNITED STATES PATENT OFFICE.

EMMETT W. STILL, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

MULTIPLE-VOLTAGE CONTROLLER.

No. 922,823.

Specification of Letters Patent.

Patented May 25, 1909.

Application filed October 31, 1906. Serial No. 341,975.

To all whom it may concern:

Be it known that I, EMMETT W. STILL, a citizen of the United States, residing at Norwood, in the county of Hamilton and State of Ohio, have invented certain new and useful Improvements in Multiple-Voltage Controllers, of which the following is a full, clear, and exact specification.

My invention relates to multiple voltage control.

It has been found that one of the most efficient ways to control an electric motor is to change its armature connections from one set of mains to another of a multiple voltage system. All the controllers which so far have been devised to do this however have been so constructed that when the change is made the armature circuit is broken in order to prevent a short-circuit between any two of the multiple voltage mains. This momentary interruption of the circuit is oftentimes disadvantageous.

It is the object of my present invention to so construct a motor controller for multiple voltage systems that the motor may be changed from one set of mains to another without necessitating an interruption of the motor circuit and without any danger of short-circuiting any two mains of the multiple voltage system.

With this object in view my invention consists broadly of the combination of multiple-voltage mains, a translating device and a controller arranged to change the connections of the translating device from any set of mains to another without opening the circuit.

In a more specific aspect my invention consists of the combination in a system of motor control, of multivoltage supply mains, a motor, and a controller therefor, said controller being constructed and arranged to change the connections of the motor armature from any set of mains to another, and as said change is made to insert resistance between those mains between which one armature terminal is being changed.

Other novel features of my invention will appear hereinafter.

Figure 1 is an elevation of the upper part of a controller embodying my invention; and Fig. 2 is a diagrammatic view showing the electrical connections of such a controller.

Referring to the drawings 10 represents a controller drum which is mounted on a shaft 11, placed in the usual casing 13 and operable by the usual handle 12. The drum here illustrated has nine operative positions and is divided into two electrical sections 14 and 15, each of these sections having a number of electrically connected contact segments 16 thereon. These segments of the controller coöperate with the stationary contact fingers 17 to 25 inclusive. The upper and lower contact fingers 17 and 25 are connected to the two terminals of the armature 26 of the motor A to be regulated. Fingers 18, 21 and 24 are connected respectively to the three mains 27, 28 and 29 of a multiple voltage system. As usual in three wire multiple voltage systems such as here illustrated, the voltages are 90, 160, and the sum of these two, 250. Connected to the contact fingers 18, 19 and 20 is a sectional resistance 30, while a similar resistance 31 is connected to the contacts 22, 23 and 24. The field winding 32 of the motor A is preferably permanently connected between the outside mains 27 and 29 of the multiple voltage system, and controlled by a separate switch 33. A main switch 34 controls the entire circuits of the motor and the controller. The strength of the field winding 32 may be regulated by a rheostat 35, which, if desired, may be combined with the controller 10.

The operation of the controller is as follows:—When the drum 10 is moved into position 1, the switches 33 and 34 being closed, the motor armature 26 is connected between the mains 28 and 29 with the entire resistance 31 in circuit. The motor now starts. As the controller is moved to positions 2 and 3 respectively, the two sections of the resistance 31 will be cut out of circuit successively. In position 3, the first running position of the controller, the armature 26 has impressed thereon the full 90 volts between the mains 28 and 29. As the controller is moved from position 3 to position 4, the contact fingers 20 and 21 are first connected together, thus connecting the mains 27 and 28 together through the entire resistance 30. This connection lasts only for an instant, as immediately thereafter the contact finger 21 breaks connection with the segment with which it had at first engaged. About this time the

resistance 31 is again included in the armature circuit. The motor armature is now momentarily connected across the high voltage outside mains, but both resistances 5 30 and 31 are fully in circuit and prevent the impressing of a too high voltage on the motor armature. Next the fingers 21 and 22 are connected by the drum section 15, thus connecting the mains 28 and 29 together 10 through the entire resistance 31. Immediately, however, the contact finger 22 is disconnected from the drum section 15. Thus in position 4 the motor armature is connected between the mains 27 and 28 with the entire resistance 30 in circuit therewith. As the drum is moved to positions 5 and 6 respectively, the two sections of the resistance 30 are successively cut out. In position 6, the second running position of the controller, 15 the armature has impressed thereon the full 160 volts between the mains 27 and 28. As the controller is moved from position 6 to position 7, the contact fingers 21 and 22 are again momentarily connected together to 20 connect the mains 28 and 29 through the entire resistance 31. Immediately, however, the contact finger 21 leaves the segment 16 of drum section 15 with which it had been in engagement in position 6. The motor armature 25 26 is now connected between the outer mains 27 and 29 with the full resistance 31 in circuit. As the controller is moved into positions 8 and 9 respectively, the two sections of resistance 31 are again successively 30 cut out of circuit. In position 9, the third and last running position of the controller, the armature 26 has impressed thereon the full 250 volts between the outer mains 27 and 29. As the controller has been moved 35 through these positions 1 to 9 the motor armature circuit has not been interrupted, short-circuiting of the mains of the multiple voltage system being prevented by means of the resistances 30 and 31. During the backward movement of the controller, the reverse of the operation just described takes place; the controller being moved from position 9 to position 1 without interrupting the motor circuit and without short-circuiting any of the mains of the multiple voltage system.

For the sake of simplicity I have shown my invention as applied to a three wire multiple voltage system but it is equally applicable to other multiple voltage systems.

The number of sections of the resistance 30 and 31 may be varied as desired to suit the requirements of the particular system. Also any desired number of motors may be simultaneously controlled. Many other modifications can be made in the precise arrangements herein shown and described, and all such which do not involve a departure from the spirit and scope of my invention I aim to cover in the following claims.

What I claim as new and desire to secure by Letters Patent is:—

1. In combination, multiple voltage mains, a translating device, a multiple voltage controller having fixed and movable contacts 70 constructed and arranged to change the connections of the translating device from any pair of said mains to another without interrupting the circuit.

2. In a system of motor control, a motor, 75 multiple voltage mains, and a controller arranged to connect the motor between any set of said mains for rotation in the same direction, and to change the connections of the motor from one set of mains to another 80 without opening the motor circuit.

3. In a system of motor control, a motor, multiple voltage mains, and a controller arranged to change the connections of the motor from any set of said mains to another 85 without interrupting the motor circuit and without short-circuiting any of the multiple voltage mains.

4. In a system of motor control, multiple voltage mains, one or more motors, a resistance, and a controller arranged to connect said motor or motors between any set of said mains for rotation in the same direction, and to change the connections of the motor or motors from one set of mains to another 95 while maintaining the continuity of the motor circuits and to properly insert the resistance while making such changes to prevent short-circuiting of any set of the multiple-voltage mains. 100

5. A controller arranged to connect a motor armature between different sets of mains, and a resistance, said controller having connections arranged to insert part of said resistance between the two mains between which an armature terminal is changed as said change is being made and to use the whole of said resistance for speed control. 105

6. In a system of motor control, a motor, multiple voltage mains, a resistance, and a controller arranged to change the connections of the motor armature from one set of mains to another while maintaining the continuity of the circuit of said armature, and as such change is being made to insert part of 110 said resistance temporarily in the armature circuit and between the two mains between which an armature terminal is being changed, different parts of such resistance being used for the two armature terminals. 115

7. In a system of motor control, a motor, multiple voltage mains, a sectional resistance, and a controller arranged to change the connections of the motor armature from any pair of said mains to another, and as such 125 change is being made to insert sections of said resistance temporarily in the armature circuit and between the two mains between which an armature terminal is changed.

8. In a system of motor control, the com- 130

- bination of a multivoltage supply circuit, a motor, and a controller arranged to connect the motor to any set of mains of the supply circuit, said controller having connections 5 for temporarily inserting a resistance in the motor armature circuit and between two mains of the supply circuit whenever a change in the connections of the armature takes place.
- 10 9. In a system of motor control, the combination of a multivoltage supply circuit, a motor, and a controller arranged to connect the motor to any set of mains of the supply circuit for rotation in the same direction, 15 said controller having connections for temporarily inserting a resistance between two mains of the supply circuit when a change in the connections of the armature takes place.
10. In a system of motor control, the combination with a multivoltage supply circuit, a motor, and a sectional resistance, of a controller constructed and arranged to change the connections of the motor armature from any set of mains of said supply circuit to another without interrupting the circuit of said armature and to insert sections of said resistance temporarily between two of the mains of the supply circuit as said change is made.
11. In a system of motor control, the combination with a multivoltage supply circuit, a motor, and a resistance, of a controller constructed and arranged to connect the motor armature between any set of mains of said supply circuit for the same direction of rotation, and to insert said resistance temporarily between two of the mains of the supply circuit as a change in the armature connections is made.
12. In a system of motor control, the combination with a multivoltage supply circuit, a motor, and a variable resistance, of a controller constructed and arranged to change the connections of the motor armature from any set of mains of said supply circuit to another without interrupting the circuit of said armature and to insert a part of said resistance between two of the mains of the supply circuit temporarily and also in the armature circuit as said change is made.
- 50 13. In a system of motor control, the combination with a multivoltage supply circuit, a motor, and a variable resistance, of a controller constructed and arranged to connect the motor armature to any set of mains of said supply circuit for the same direction of rotation and to insert portions of said resistance between two of the mains of the supply circuit temporarily and also in the armature circuit as a change in the armature connections is made.
14. In a system of motor control, the combination with a multivoltage supply circuit, a motor, and a variable resistance, of a controller constructed and arranged to change 65 the connections of the motor armature from any set of mains of said supply circuit to another without interrupting the circuit of said armature and to insert part of said resistance between two of the mains of the supply circuit temporarily and also in the armature circuit as said change is made, and to gradually cut said resistance out of the armature circuit.
15. In a system of motor control, the combination with a multivoltage supply circuit, a motor, and a variable resistance, of a controller constructed and arranged to change the connections of the motor armature from any set of mains of said supply circuit to another and to insert part of said resistance between two of the mains of the supply circuit temporarily and also in the armature circuit as said change is made, and to gradually cut said resistance out of the armature circuit.
16. In a system of motor control, the combination of multivoltage supply mains, a motor, and a controller therefor, said controller being constructed and arranged to change the connections of the motor armature from any set of said mains to another, and as such change is made to insert a resistance between those mains between which an armature terminal is being changed.
17. In a system of motor control, the combination of multivoltage supply mains, a motor, and a controller therefor, said controller being constructed and arranged to change the connections of the motor armature from any set of said mains to another, and as such change is made to insert a resistance between those mains between which an armature terminal is being changed and also to insert a resistance in the armature circuit.
18. In a system of motor control, the combination of multivoltage supply mains, a motor, and a controller therefor, said controller being constructed and arranged to change the connections of the motor armature from any set of said mains to another without breaking the circuit of said armature, and as such change is made to insert a resistance between those mains between which an armature terminal is being changed.
19. In a system of motor control, the combination of multivoltage supply mains, a motor, and a controller therefor, said controller being constructed and arranged to change the connections of the motor armature from any set of said mains to another without breaking the circuit of said armature and as such change is made to insert a resistance between those mains between which an armature terminal is being changed, and also to insert a resistance in the armature circuit.
20. In a system of motor control, the combination of multivoltage supply mains, a motor, and a controller therefor, said controller being arranged to change the connections of the motor armature from any pair of said mains to another without interrupting

the circuit of said armature, and when making said change to properly insert resistances to prevent a too sudden variation of voltage on said armature or a short-circuit between any two of the supply-mains.

21. In a system of motor control, the combination of multivoltage supply mains, a motor, and a controller therefor, said controller being arranged to change the connections of the motor armature from any set of said mains to another without interrupting the circuit of said armature, and when making said change to properly insert resistances to prevent a short-circuit between any two of the supply mains.

22. In a system of motor control, the combination of multivoltage supply mains, a motor, and a controller therefor, said controller being arranged to connect the motor armature between any set of said mains for rotation in the same direction, and when making a change in the armature connections to properly insert resistances to prevent a too sudden variation of voltage on said armature or a short-circuit between any two of the supply mains.

23. In a system of motor control, the combination of multivoltage supply mains, a motor, and a controller therefor, said controller being arranged to change the connections of the motor armature from any set of said mains to another, and when making said change to properly insert resistances to prevent a short-circuit between any two of the supply mains.

24. In a system of motor control, the combination of multivoltage supply mains, a

motor, and a controller therefor, said controller being constructed and arranged to change the connections of the motor armature from any set of the mains to another by first connecting the armature terminal to be changed to the main desired and then disconnecting it from the main to which it had been originally connected.

25. In a system of motor control, the combination of multivoltage mains, a motor, a controller therefor, and a resistance, said controller being arranged to change the connections of the motor armature from any set of the mains to another by first connecting the armature terminal to be changed to a point on the resistance and the resistance between the mains between which said terminal is to be changed, and then disconnecting said terminal from the main to which it had been first connected.

26. A controller arranged to connect a motor armature between different sets of mains, and a resistance, said controller having connections arranged to insert part of said resistance between the two mains between which one armature terminal is changed as said change is being made and another part of said resistance between the mains between which the other armature terminal is changed as said latter change is being made.

In testimony whereof I affix my signature, in the presence of two witnesses.

EMMETT W. STULL.
